UNITED STATES PATENT OFFICE.

FRANK L. IRWIN, OF COLUMBUS, OHIO, ASSIGNOR TO THE RALSTON STEEL CAR COMPANY,
OF COLUMBUS, OHIO.

STEEL UNDERFRAMING FOR RAILWAY-CARS.

No. 882,638.

Specification of Letters Patent. Patented March 24, 1908.

Application filed April 15, 1907. Serial No. 368,375.

To all whom it may concern:

Be it known that I, FRANK L. IRWIN, of Columbus, in the county of Franklin and State of Ohio, have invented certain new and useful Improvements in Steel Underframing for Railway-Cars, and I do hereby declare the following to be a full, clear, and exact description of the invention, such as will enable others skilled in the art to which it appertains to make and use the same.

My invention relates to improvements in steel underframing for railway cars, an object of the invention being to provide depressed supports for the side-sills at the ends of the cross-bearers and bolsters, whereby side-sills of sufficient strength can be used and so disposed that their upper faces will be in alinement with the upper faces of the intermediate longitudinal sills or stringers for the reception of the car flooring.

A further object is to provide cross-bearers of simple construction and to so secure them in place as to effect their rigid and substantial connection with the center girder.

With these objects in view the invention consists in certain novel features of construction and combinations of parts as hereinafter set forth and pointed out in the claims.

In the accompanying drawings, Figure 1 is a perspective view of a car under-frame embodying my improvement. Fig. 2 is a transverse section of the lower portion of a car adjacent to one of the cross-bearers, and Figs. 3, 4 and 5 are fragmentary views illustrating certain modifications.

1 represents the center girder of the box type,—comprising channel-iron members 2, 3, a bottom plate 4 and a cover plate 5. Each end of each girder member 2, 3, is split vertically and the metal bent laterally, forming seats 6 for an end sill. In rear of these seats the center girder members may be connected by a brace plate 7. Adjacent to the ends of the center girder, the bolsters 8 are located. Each bolster comprises two pairs of channel-irons 9 spaced apart. Each bolster member abuts at its inner end against a side of the center girder and is secured thereto by means of angle brackets 10. A cover plate 11 is placed upon each bolster, extending across the members thereof, and passes through the sides of the center girder, the ends of said cover plate terminating an appreciable distance from the respective ends of the bolster. Each bolster member is slit vertically near

its outer end and the metal then bent laterally to form seats 12 for a side sill 13, two such seats being thus formed at each end of each bolster. Bracing angles 14 are located between the bolster members, at their outer ends.

Cross-bearers 15 are located at intervals along the center girder between the bolsters. Each cross-bearer comprises two channel-iron members 16, each abutting at its inner end against the side of the center girder and are secured thereto by angle brackets 17. An angle iron truss 18 is disposed, between its ends against the bottom of the center girder and its end portions are bent upwardly and secured to the respective members of the cross-bearer. This truss is also secured to the flanges at the bottom edges of the center girder. The outer end of each cross-bearer is made with a depressed seat 19 for the side sills. These seats may be made in the manner above described in connection with the bolsters. That is to say each member of the cross-bearer is slit vertically near its outer end and the metal bent downwardly until it assumes a horizontal position parallel with the top of the cross-bearer. Each cross-bearer is provided with a cover plate 20 which extends through the center girder and bolted or riveted upon the respective members of the cross-bearer.

Several intermediate longitudinal sills or stringers 21 are located between the center girder and the side sills and are supported upon the bolsters and cross-bearers so that their upper faces will be in the same horizontal plane as the upper surfaces of the side sills, and to said upper surfaces of the side sills and intermediate sills the flooring 22 of the car is secured.

By means of the construction and arrangement of parts as above set forth, it will be seen that wooden side sills of adequate size and strength to sustain the super structure can be employed.

If desired brackets 24 may be secured to the cross-bearers to form extended bearings for the intermediate sill, and similar brackets 25 may be secured to the center girder near the respective ends thereof for the same purpose. Instead of forming the seats for the side-sills at the ends of the cross-bearers, by slitting and bending, as above described,—the depressed seats may be made by pressing as shown at 23 in Fig. 3.

If desired, each member of the cross-bearers may consist of two channel-irons placed back to back, as shown in Fig. 4, and the depressed seats for the side-sills formed by slitting and bending, as before explained. When this construction of cross-bearer is employed the two channel-iron members may be slightly separated to receive the end of the truss 18 between them,—in which case the top flange of the truss may be removed, as shown in Fig. 5, or the channel iron members may be placed back to back and the truss secured to the bottom flanges.

Other slight changes might be made in the details of construction of my invention without departing from the spirit thereof or limiting its scope, and hence I do not desire to limit myself to the precise details herein set forth.

Having fully described my invention what I claim as new and desire to secure by Letters-Patent, is:—

1. In a car underframe, the combination

with a center girder, of transverse members secured thereto, each of said transverse members slit vertically near the outer end and bent laterally and downwardly, forming depressed seats for longitudinal members, and a bracing member secured to the center girder and to the side of the transverse member.

2. In a car underframe, the combination with a center girder, of a cross bearer comprising a plurality of transverse members secured to the center girder, the outer end of each transverse member slit vertically and bent laterally and downwardly, forming a depressed seat for a longitudinal member, and bracing means secured to the side faces of the cross bearer members.

In testimony whereof, I have signed this specification in the presence of two subscribing witnesses.

FRANK L. IRWIN.
